UNITED STATES PATENT OFFICE

MATTHÄUS STUMP, OF MANNEIM, AND KURT REYHER, OF HEIDELBERG, GERMANY

DEVICE FOR ASCERTAINING THE ENERGY SPENT DURING ROWING

Application filed February 28, 1928, Serial No. 257,697, and in Germany March 23, 1927.

This invention relates to a device permitting ascertaining and recording automatically the energy which an oarsman spends while he is rowing. We are aware of the fact that there exist already devices for this object but with them the pressure exerted upon the oar blade by the water is used as source of power for moving a piston or a diaphragm which in turn operates a writing member by the intermediary of a Bowden cable or the like. In contradistinction thereto in our invention the deformation which the oar staff undergoes while the oar is being pulled is employed as means for operating the writing member which co-operates with the recording drum which is attached to the oar staff. The use of long transmission members as with the devices employed hitherto gives rise to faulty records; this is obviated with the present improved construction.

Our invention is illustrated diagrammatically and by way of example on the accompanying drawings, on which Figure 1 is a diagrammatic plan of the entire arrangement and combination of parts constituting our improved device; Figure 2 is a diagrammatic side view of that arrangement and combination of parts, the actual position of the axis of the drum (11) relatively to the cord (8) actuating the writing lever 10 being, however, left out of consideration; Figure 3 is a view similar to Fig. 1, but showing the parts drawn to an enlarged scale, and Figure 4 is an end-view of the device showing it seen in the direction from the righthand end of Fig. 3 to the lefthand end thereof.

On the drawings, 1 denotes the oar staff to which are attached clamps 2 and 3 by means of screw-threaded spindles 19. Each clamp 40 has a lateral projection 18, and the two projections 18 are connected with one another by a flat ledge 14, to which they are pivotally connected, and from the middle portion of which projects laterally forth a pin 17 supporting a record drum 11. Between this drum and the ledge 14 a disk 15 is also firmly connected with the middle portion of the ledge 14, and from the lower portion of the disk project laterally forth two brackets 16 45 serving as bearings for a pin 20 supporting

a small roll 9 to which is affixed one end of a cord 8, the other end of which is connected with a wire 6 extending from the lower end of a vertical arm 5 to the lower end of a like arm 4, these two arms being firmly connected 55 with the brackets 3 and 2. The connection between the arms 4, 5 with the wire 6 is effected by means of one or two threaded pins 7^a, and nuts 7 that are adjustable on the pins, the wire ends being connected with the pins, 60 these latter being supported in the arms 4 and 5, and each pin bearing two nuts 7, the one on the one side of the appertaining arm and the other nut on the other side of the respective arm. It is obvious that the wire 6 65 can be put under tension by these means and that the tension can be regulated.

The small roll 9 is firmly connected with a lever or arm 10 which is subjected to the pull of a helical tension spring 13 tending continually to counteract the pull of the cord 8, or of this cord and the wire 6 together respectively. At the free end of the arm 10 is a writing member 10^a and the drum 11 is covered with a suitably ruled sheet of paper on 75 which the writing member writes the record.

The disk 15 is attached to the ledge 14 not directly, but by means of an intermediary member 15^a in which is a vertical slot traversed by the pin 17, and this latter is firmly 80 connected in said slot with a roll 12^a to which is attached one end of a cord 12, the other end of which is affixed to a suitably located point of the boat.

This combination and arrangement of the 85 several parts renders it possible to obtain either closed or continuous records on the drum when the boat is driven by the oars. The manner of operation is as follows:

When the oar bearing the device is pulled, 90 its staff is bent through more or less according to the amount of force spent (see the dotted lines in the uppermost part of Fig. 2), and owing thereto also the position of the arms 2 and 3 relatively to each other will 95 change (Fig. 2); this is true, obviously, also of the wires 6 and 8, as well as of the writing member 10^a with respect to the drum 11, as the member 10^a is subjected to the action of the wire 8, as well as to the action of the 100

spring 13. There is, thus, a record made on the drum 11 while the oar is actuated in the known manner. To fully understand the operation it must be borne in mind that the drum is rotated by the intermediary of the cord 12, and it is a matter of course that the drum is combined with a spring which is put under tension when the drum is moved off the point where the cord 12 is affixed to the boat, this spring turning the drum in the other direction when the drum is moved by and with the oar in the direction to said point.

10 The ordinates of the diagrams indicate the energy spent, and the abscissæ indicate the length of time during which that energy had been spent. The curve indicates the distribution of the energy over that time and constitutes a characteristic of the performance.

15 Differences in the elasticity of the oar staff are compensated by changing correspondingly the tension of the wire 6 by means of the nut 7.

20 We wish it to be understood that the change of the distance between the points 4 and 5 can be transmitted to the writing member or lever 10 also by other means than those shown in the drawing merely by way of example. The points 4 and 5 can be arranged in the tensile zone, as well as in the compressive zone 25 of the oar.

25 When the cord 12 is used, the drum 11 is rotated alternately in the one and the other direction, but it is also possible to turn the drum continuously in only one direction in which case a wheel-work for it is provided. It is obvious that also other recording means may be made use of. If the drum is turned continuously there are produced continuous diagrams which can be read in the same manner as those obtained with the arrangement and combination of parts shown in the drawing.

30 We claim:

1. A device for ascertaining the energy spent during rowing, comprising, in combination with the oar, arms projecting forth from the staff of the oar in a certain distance from each other; a recording drum, and means adapted to transmit the changes of the distance between the free ends of said arms to said drum so as to obtain a record of them.

35 2. A device for ascertaining the energy spent during rowing, comprising, in combination with the oar, arms projecting forth from the staff of the oar in a certain distance from each other, a recording drum and a writing member co-operating with it, a wire stretched out between the free ends of said arms, and means for transmitting the changes of the tension of said wire to said writing member.

40 3. A device for ascertaining the energy spent during rowing, comprising, in combination with the oar, arms projecting forth from the staff of the oar in a certain distance from each other, a recording drum and a writing

member co-operating with it, a wire stretched out between the free ends of said arms, a roll connected with said writing member, another wire connecting said roll with the first-mentioned wire and adapted to transmit changes of the tension of it to the drum so as to turn it, and yielding means counter-acting the pull of said other wire, substantially as set forth.

45 In testimony whereof we affix our signatures.

50 MATTHÄUS STUMP.
KURT REYHER.
